POLISHING DEVICE

Alfred J. Stecker, Detroit, Mich.

Application February 23, 1934, Serial No. 712,511

1 Claim. (Cl. 15—230)

This invention relates to a power driven, hand operated polishing device and more particularly to the construction of the device including a flexible driving connection between a driving and a driven member thereof.

An object of the invention is to provide a device for the purpose including a rotatable polishing member having a substantially flat side covered by a suitable material to engage and polish the surface of the work, and a motor driven driving member connected to said polishing member at the axis thereof by a flexible member for transmitting rotary motion from said driving to said polishing member and adapted to permit lateral tilting of said driver relative to said polisher, so that said polisher may follow the surface of the work, regardless of the angular position of the driver relative to said polisher.

A further object is to provide an arrangement whereby the flexible driving connection between driver and polisher, will yield to provide a soft yielding pressure of the polisher upon the surface of the work; and further, to provide a construction of polisher wherein the flat side and peripheral rim thereof are covered by a covering of soft fibrous material which may be conveniently removed and replaced and which forms an even, rounded peripheral polishing edge for the polisher.

A further object is to provide a small power driven polisher having a construction which particularly adapts it for use in polishing uneven or curved surfaces by manipulation of the device as a unit while held in one hand by the operator, said unit embodying an electric motor and being light in weight, simple in construction, and having certain other new and useful features, all as hereinafter set forth, reference being had to the accompanying drawing wherein—

Figure 1 is a side elevation of a device illustrative of an embodiment of the present invention;

Fig. 2 is a transverse axial section through the polisher head, detached;

Fig. 3 is a plan view of the polisher; and

Fig. 4 is a sectional detail of the polisher head showing a slightly modified construction.

The device as a whole, is shown in Figure 1 and comprises a small electric motor the casing 1 of which is formed at one end with an axial hub 2 into which the armature shaft 3 of the motor extends and this hub is formed with a lateral housing 4 having a bearing boss 5 extending downwardly from its lower side to a plane below the horizontal plane of the lower side of said cas-

ing 1 and forming a bearing within which a vertical shaft 6 is mounted, any suitable gearing 7 being housed within said housing 4 for transmitting motion from the shaft 3 to the upper end of said shaft 6. Secured to the top of said housing is a bracket 8 for supporting a handle 9 in horizontal position above and spaced from said casing 1.

A polisher head or wheel, indicated as a whole by the numeral 10, is detachably secured to the projecting lower end of said shaft 6 and is of circular form with a substantially flat lower side and curved periphery covered by a fibrous material to engage the work, said polishing head or member with said motor provided with a handle, 15 forming a unit which may be easily manipulated by one hand of the operator to pass the polisher over the surface to be polished, with just the desired pressure, the weight of the motor assisting in giving this pressure and in steadyng the 20 polisher to prevent vibration and to give it the proper even contact with the work.

In order that the polishing head or wheel may follow the contour of the surface being polished, no matter in what angular position the driving 25 shaft 6, which is driven by the motor, may be relative to said surface or head, a flexible connection is provided between said shaft and head, said driving connection comprising preferably, a disk 11 of rubber or other suitable material, this disk 30 having a center opening to receive the externally screwthreaded and reduced lower end of a collar 12 having an axial bore to receive the end of the shaft 6 to which said collar is detachably secured by a set screw 13, and to secure the central portion of this disk to said collar, a nut 14 is screwed upon the reduced end of said collar with a ring 15 interposed between said nut and collar to firmly clamp this central portion of the disk to the collar. 40

The polishing head or wheel comprises a sheet metal disk 16 having an upturned peripheral edge 17 and secured over the lower flat face of this disk and rolled upwardly and over said upturned edge flange, is a layer of sheepskin 18 45 with natural wool 19 thereon, and interposed between this skin and disk is a layer 20 of any suitable material such as canvas or the like, with the edges of both layers extended upward and over the edge flange of said disk and drawn inwardly by means of suitable, preferably flexible lacing 21 to hold the layers flat upon the face of the disk with the wool extending from the outer layer and with the layers curved inwardly and over the upturned edge of the disk to form a 50 55

- smooth round peripheral edge for the head, which edge is of considerable thickness in cross section with the wool covering projecting therefrom, thus forming a peripheral buffing or polishing edge for the head with the wool or other fibre covering said edge to prevent it from coming into contact with any projecting portion of the work and injuring the same. This edge so covered, thus provides a comparatively narrow buffing or polishing portion for the head.
- To attach the disk 18 to the periphery of the flexible rubber disk 11, a ring 22 of considerable width vertically is secured upon the upper face of the disk 16 concentric therewith, and the edge portion of this rubber disk is secured thereto by means of a clamping ring 23 laid thereon and the rings secured together with the edge portion of said disk 16 clamped therebetween, by screws 24 passing through said disks and rings.
- The space between the disks 11 and 16 and within the ring 22 may thus form a substantially air tight chamber 25 which will act as an air cushion beneath the rubber disk 11 to prevent too free flexure or collapsing thereof under pressure thereon applied through the shaft 6 in forcing the head against the surface being polished.

Preferably as shown, the flexible disk 11 which connects the polishing head with the end of the drive shaft 6, is cupped to offer further resistance to downward flexure and prevent the nut 14 from coming into contact with the disk 16, the cupping of said rubber disk providing a greater area thereto, so that it will more easily flex and give a soft cushioning of the head upon the work, but

this rubber disk is of sufficient thickness to provide an adequate driving connection between said shaft and head.

Obviously as shown in Fig. 4 the ring 22 may be omitted if desired, the peripheral portion of the flexible disk 11 being secured directly to the metal disk 16, and as a substitute for the lacing 21 an expansion ring 26 may be provided to detachably hold the edges of the layers 18 and 20, the flange 17 being curved inwardly to form a channel to receive said edges with said ring expanded thereagainst, thus clamping said edges within said channel.

Obviously other changes in the construction, arrangement or size and proportion of the parts 18 may be made within the scope of the appended claim without departing from the spirit of the invention, and such changes are contemplated.

Having thus fully described my invention, what I claim is:—

A polishing device comprising a polishing head having a substantially flat work contacting side, a driving shaft, and a flexible disk-like cupped member connected centrally to the end of said shaft and at its marginal portion to said head to form a closed air chamber between said disk and head and adapted to yield upon lateral tilting of said shaft relative to said head when said head is moved with its work contacting side in contact with an irregular surface of the work, the confined air in said chamber serving to support said disk under endwise force of said shaft applied thereto.

ALFRED J. STECKER.
